[57] CLAIM

The ornamental design for tweezers, as shown and described.

DESCRIPTION

FIG. 1 is a plan top view of a first embodiment of the subject perforated tweezers with a perforated top leg and an unperforated bottom leg;

FIG. 2 is a plan bottom view of the tweezers of FIG. 1;

FIG. 3 is a side view of the tweezers of FIG. 1;

FIG. 4 is a perspective view of the tweezers of FIG. 1, the undisclosed left side and inner surface following the contours of the sides shown;

FIG. 5 is a plan top view of a second embodiment of the subject perforated tweezers with both legs having perforations; and,

FIG. 6 is a plan bottom view of the tweezers of FIG. 5 the undisclosed sides of this embodiment being identical to the first disclosed embodiment except for the appearance of the perforations on the bottom leg.
